GARMENT DISPLAY FORM

Julius Mayer, Forest Hills, N. Y.

Application December 21, 1945, Serial No. 636,418

4 Claims. (Cl. 223—72)

1

This invention relates to new and useful improvements in garment display forms and more particularly to a form for displaying waist band garments such as trousers, slacks, and skirts in simulation of their position when worn by a user.

One of the main features of the invention resides in a trousers display form for use in displaying trousers in show windows and stores in a manner to impart a natural hang to the trousers so displayed.

Another feature of the invention is to provide a display form which is more readily adjustable to the trousers and will automatically engage the waist portion therefor when in position.

Another object is to provide a form which can be much more quickly applied to and removed from the displayed garment.

A further object is to provide a simple, efficient, durable, inexpensive display form which is composed of relatively few parts, which can be adjusted to the trousers with ease of adjustment and yet which can be knocked down and stowed away quickly in a very small compass.

Further and more specific objects, features and advantages will more clearly appear from a consideration of the specification hereinafter especially when taken in connection with the accompanying drawing which forms part of the specification and which illustrates a present preferred form which the invention may assume.

Generally and briefly the invention includes a display form frame comprising spaced upright legs with feet at the bottom and a cross connecting member at the top forming a substantially rigid generally rectangular frame which will stand on the floor or a show window and support a garment, such as a pair of trousers, thereon. At the ends of the cross connecting member are disposed waist engaging form members movably disposed thereon and means associated between the cross connecting member and the waist engaging form members to automatically at all times press the waist engaging form members outwardly to forcibly engage the waist portion of the garment. Preferably the cross connecting member is a tube of definite length for any particular display form and within its open ends project members disposed telescopically therein. Springs in the cross connecting member press outwardly on the telescopic members to tend to move them outwardly at all times and the waist engaging form members are disposed on the outer ends of the telescopic members.

This provides a construction which permits the operator to fit the device, at the waist, merely by

2

pressing inwardly on the waist engaging form members to momentarily press them towards each other while he is adjusting the waist of the garment around them after which he merely lets go of them and the springs will force them into engaging position.

Other features will appear from a consideration of the following detailed specification and in the appended claims which set forth my invention.

10 The present preferred form which the invention may assume is illustrated in the drawing, of which,

Figure 1 is a perspective view of an adjustable trouser display form constructed in accordance with the invention, a pair of trousers being illustrated in dotted lines.

Figure 2 is a top plan view.

Figure 3 is an enlarged vertical sectional view taken substantially on the line 3—3 of Figure 2.

15 Figure 4 is an enlarged detailed vertical sectional view on the line 4—4 of Figure 1.

Referring to the drawing by reference characters, the numeral 10 denotes my adjustable trouser display form in its entirety which in-

20 cludes a stand embodying a pair of spaced apart vertical legs 11. These legs are of different lengths depending upon the length of the trousers or other garment which they are to support. Connected to the lower end of each leg 11 is a

25 foot 12 which may be in the form of a flat bar or tubular in shape. The lower end of each leg 11 has a reduced threaded end 13 which screws into a threaded hole 14 of its related foot 12. The feet 12—12 may be definitely spaced by means of a pair of connecting cross bars 15. The feet 12 extend forwardly and rearwardly a distance to provide a supporting base for the legs 11. The legs 11 and the feet 12 form leg units which are substantially inverted T-shape and which are sufficiently rigid to support the load to which it is subjected when in use.

30 The upper end of each leg 11 is fitted into a socket 16 of a collar member 17 which is fastened rigidly in any suitable manner near the ends of a tubular element 18 of predetermined length depending upon the size of the form being used. The upper end of each leg is held in its socket by means of a set screw 19. Telescopingly fitting into the ends of the tubular element 18 are rods

35 or hollow tubes 20 the open ends of which face each other. The tubular element 18 has a pin 21 across it near the center thereof and this pin acts as a bearing member for the inner ends of springs 22 which separately extend from the pin 21 to the outer closed ends of the hollow tubes 20

thus tending at all times to push these tubes out of the tubular element 18. An air hole 23 is provided in the tubular element 18 to permit free movement therein of the telescopingly disposed tubes 20.

It will therefore be seen that the feet 12, the legs 11, the collars 17 and the tubular element 18 form a firm substantially rigid strong frame for supporting the trousers to be suspended therefrom. To suit different sizes of trousers, the tubular elements 18 can be of different lengths and the collars 17 may be disposed at different distances from the ends thereof.

The adjustable waist form member 24 includes a pair of arcuate-shaped form sections 25 and 26 with convex outer faces fixedly secured at their mid-portions to the outer ends of the telescoping hollow tubes or elements 20 respectively. Thus it can be seen that these waist form sections will at all times be urged outwardly by the springs 22 to press against the inner portions of the waist of the supported garment. These form sections 25 and 26 are arranged with their concave sides in spaced confronting relation as best illustrated in Figure 2.

Means are provided for limiting the sliding movement of the tubes 20 relative to the tubular element 18. Each of such means comprises a pin 28 carried by a tube 20 which extends into a slot 29 in an adjacent portion of the tubular element 18.

The legs of the trousers T hang down from the waist engaging form 24 with the legs 11 enclosed therein. In order to impart a natural fullness to the lower portions of the trouser legs, I may mount leg form members 27 upon the lower leg portions 11. These may be of any shape and construction but are preferably of the construction shown in my co-pending application Serial No. 617,837, filed September 21, 1945.

To support a pair of trousers upon the form 10, the leg sections are separated from the collars 17 by releasing the set screws 19 whereupon the upper portion of the form can be removed from the leg sections. The legs of the trousers are then slipped down upon each leg 11 and past the form sections 27 which have been previously adjusted to the proper dimensions for the trousers being displayed.

The upper unit is then placed in position on the legs 11 by inserting the upper ends of the legs 11 into their respective sockets and tightening up the set screws 19. However while this is being done the hands of the operator must press inwardly on the waist form members 25 and 26 so as to push them in against the outward thrust of the springs 22 to a contracted position. This will dispose the form members 25 and 26 well within the outline of the waist of the trousers until the upper portion of the form is in place, whereupon the waist form members 25 and 26 can be released and allowed to expand or move outwardly, under the action of springs 22, to press against the waist of the trousers and automatically keep them in proper position and shape.

The relation between the length of the trouser legs and the height of the display form can be adjusted to suit by providing a series of sets of legs 11 of different length which can be readily substituted the one for the other as the case may require. It will rarely be necessary to substitute

for the horizontal tubular member 18 since the expansion and contraction possible to the waist form members 25 and 26 will adapt the upper portion to use with almost any range of garment 5 waist band size.

For packing and shipping and for storage purposes, the form can easily be knocked down as will readily be seen. The legs 11 can be unscrewed from the feet 12 and disconnected from the collars 17 by releasing the set screws 19, thus enabling the several parts to be stowed away in very small compass.

While the invention has been described in detail and with respect to a present preferred form 15 which the invention may assume, it is not to be limited to such details and forms since many changes and modifications may be made in the invention without departing from the spirit and scope of the invention in its broadest aspects. 20 Hence it is intended to cover any and all forms and modifications of the invention which may come within the language or scope of any one or more of the appended claims.

Having thus described the invention, what I 25 claim as new and desire to secure by Letters Patent, is:

1. A trousers form display device comprising a stand having spaced apart legs over which the legs of trousers are adapted to be loosely fitted, 30 a horizontal member connecting the upper ends of the legs, waist engaging form members with convex outer faces movably disposed on the ends of the cross connecting member, and spring means associated with the cross connecting member and the waist form members to press the waist form members outwardly at all times.

2. A trousers form display device comprising a stand having spaced apart legs over which the legs of trousers are adapted to be loosely fitted, 40 collars into which the upper ends of the legs are removably inserted, a fixed horizontal tubular member on which the collars are disposed, elements inserted into the ends of the tubular cross member, resilient means in said member to press outwardly at all times on the elements, and waist form members having convex outer faces disposed on the outer ends of said elements.

3. A trousers form display device comprising a pair of arcuate-shaped waist form members with 50 their concave sides facing each other, hollow tubes connected to the inner mid-portions of said waist form members, a tubular cross connecting member into the ends of which said hollow tubes extend, a pin extending across the tubular cross connecting member near its mid-portion, springs 55 within the tubular cross connecting member and with their inner ends bearing against the pin, the outer ends of said springs bearing against the hollow tubes to force the waist form members outwardly at all times, collars on the ends of the tubular cross connecting member, upright leg members removably inserted into sockets on said collars, and feet members at the bottom of the leg members and threadably engaged.

4. A trousers form display device as set forth 60 in claim 3 including means between the hollow tubes and the connecting member for limiting the sliding movement of the tubes in opposite directions.
